UNITED STATES PATENT OFFICE.

ABRAHAM FISCHER, OF HILLSBORO, KANSAS, ASSIGNOR OF ONE-THIRD TO WILLIAM H. DE WALT AND ONE-THIRD TO PETER P. BARKMAN, BOTH OF HILLSBORO, KANSAS.

SIGN-STRETCHER.

1,194,610.

Specification of Letters Patent. Patented Aug. 15, 1913.

Application filed November 10, 1915. Serial No. 60,756.

To all whom it may concern:

Be it known that I, ABRAHAM FISCHER, a citizen of the United States, residing at Hillsboro, in the county of Marion and State of Kansas, have invented certain new and useful Improvements in Sign-Stretchers, of which the following is a specification, reference being had to the accompanying drawings.

10 My invention relates to devices for stretching signs or for cognate purposes, and the general object of my invention is to provide a very simple, convenient, easily operated and effective device of this character by which a sign or sheet of flexible material may be stretched and held in a taut or stretched condition.

20 A further object of the invention is to provide a device which is adapted to hold two signs or two sheets of flexible material in parallel relation and in a stretched condition.

25 Still another object is to provide means whereby the sheet of flexible material containing the sign may be stretched both longitudinally and laterally, and still another object is to provide means whereby the sheet containing the sign may be readily attached to or removed from the stretcher without in 30 any way marring the sheet, thus permitting the signs to be changed when desired.

Other objects will appear in the course of the following description.

35 My invention is illustrated in the accompanying drawings, wherein:

Figure 1 is a face view of my improved sign stretcher, partly in section, and showing the device in operation; Fig. 2 is a top plan view of the construction shown in Fig. 40 1, the nut 9 being removed; Fig. 3 is an enlarged fragmentary plan view of the end of one of the strips showing the gripping devices, the plate 22 being partly in section; Fig. 4 is a section on the line 4—4 of Fig. 3; Fig. 5 is a section on the line 5—5 of Fig. 3; Fig. 6 is a top plan view of the supporting bracket; Fig. 7 is a fragmentary view, partly in section, of the upper end of the section 2; and Fig. 8 is a like view of the 50 lower end of the section 3.

Referring to these figures it will be seen

that my improved sign stretcher comprises a telescopic stretcher bar composed of the tubular section 2 and the inserted longitudinally shiftable section 3. These sections 2 and 3 are preferably in the form of tubes though not necessarily so, the section 3 being contained in the section 2. The section 3 is provided with a plurality of ratchet teeth 4 and the section 2 is provided with a pawl 5 which will engage with the teeth 4 and will hold the section 3 in any longitudinally adjusted relation to the section 2 against the elasticity of the sign supported in the spreader. This pawl 5 is shown as pivoted to the section 2, projecting through a slot and as having its outer end beyond the pivot greater in weight than its inner end so that it will normally occupy a position where it will engage with the teeth 4. When it is desired to release the pawl it is only necessary to press inward upon the projecting end of the pawl which will release it from the teeth 4. A bracket 6 or other supporting member is mounted upon the section 2. As illustrated this bracket is composed of two members together embracing the section 2 and adapted to be engaged with any suitable support, the sections of the bracket being held together by bolts so that the bracket 80 may be clamped tightly upon the section 2. At its upper end the section 2 is formed with a square shank 7 and beyond this square shank with a screw threaded portion 8 adapted for engagement by a nut 9. The lower end of the section 2 is likewise 85 formed with a square portion 10 and a screw threaded portion 11 adapted to be engaged by a nut 12.

90 Mounted upon the opposite ends of the sections 2 and 3 are the resilient semicircular strips 13. These strips are alike in form. Each strip is somewhat resilient and at its center is provided with a square opening for the reception of the square shank of the 95 respective sections. Each strip constitutes a pair of arms yieldably connected to the corresponding section of the stretcher bar, each freely movable with relation to each other and the stretcher bar and normally held by the resilience of the material of the strip in divergent relation and at more than 100

a right angle to the corresponding stretcher bar. The strip 13 at its extremities is so formed as to provide means for gripping two flexible sheets or signs designated generally A. To this end each extremity of each of the strips 13 is downwardly bent, as at 14, and then inwardly bent as at 15. This inwardly bent extremity 15 has the upwardly projecting ears 16 on each side whose ends are inwardly bent, as at 17, to extend beneath the extremity of the strip 13 and be riveted thereto by the rivets 18. This provides at each end of the strips the side plates 16. Extending across the end 14 of each strip is a plate 19 which is riveted thereto and provided with the inwardly curved and rearwardly projecting resilient ears 20. These ears normally bear resiliently against the confronting plates 16 but may be forced inward and into gripping relation with the plate 16, as by means of an angular lever 21 which is disposed through a slot in the corresponding end of a plate 22 which is likewise riveted across the face of the end portion 14. It will be seen that when the levers 21 are turned to the position shown on the upper side of Fig. 2, the spring ears 20 will be released, but when the lever is turned to the position shown on the lower side of Fig. 2, the spring ears will be turned inward into gripping relation to the plate 16 and the corner of the sign engaged by such spring ears will be firmly gripped and held.

The operation of this invention is obvious from what has gone before. Primarily, as before stated, this invention is designed for the purposes of stretching signs which are painted upon canvas or other flexible material. The corners of the sign are inserted beneath the spring ears 20 and the levers 21 turned down to clamp the sign firmly in place. The members 2 and 3 are then shifted longitudinally outward relative to each other, and as this is done the resilient strips 13 tend to flatten, forcing the corners of the sign not only outward but laterally, thus stretching the sign evenly and in all directions so that the sign is held perfectly flat. For the purpose of permitting the ready pulling down of the member 3 relative to the member 2, which last member is supported by means of the bracket 6, I attach to the extremity of the member 3 the handle 23 having an eye for the insertion of a finger of the operator. It will be seen that when the members 2 and 3 are shifted away from each other the pawl will hold these members in their shifted position and will not let the contraction of the sign cause the contraction of the stretcher.

While I have illustrated certain details of construction, which I believe to be most effective in practice, I do not wish to be limited thereto as it is obvious that many changes

might be made in these details without in any way departing from the spirit of my invention as claimed.

Having thus described the invention, what I claim is:

1. A stretcher of the character described comprising a supporting member, oppositely bowed resilient end members attached to opposite ends of the supporting member, and means on the ends of said end members for gripping the article to be stretched. 70

2. In a stretcher of the character described, a supporting member made in two sections and longitudinally expandable and contractible, means for holding said sections in any adjusted relation, and end members mounted upon the opposite ends of said sections, each end member consisting of two divergent arms resiliently held in divergent relation and against movement into a position of alinement, each of said arms being movable relative to the supporting member. 80 85

3. In a stretcher of the character described, longitudinally adjustable stretcher sections, oppositely bowed resilient end members mounted each upon an end of one of the sections, the end members when so disposed being in oppositely bowed relation, latching means holding the stretcher sections in adjusted position and normally preventing their collapse, and means upon the extremity of the end members for gripping the corners of an article to be stretched. 90 95

4. A stretcher of the character described comprising a tubular stretcher section and a stretcher section having telescopic relation to the tubular section, said last named section being formed with ratchet teeth, a pawl carried by the tubular section and engaging said ratchet teeth, a support operatively connected to the tubular section, end members attached each to the outer end of one of said stretcher sections, each member consisting of a resilient bowed strip, the arms of one strip extending in a divergent relation to the arms of the opposite strip, and means on the extremities of the strips for engaging with the corners of an article to be stretched. 100 105 110

5. In a stretcher of the character described, a support comprising relatively longitudinally adjustable sections, means for holding the stretcher sections in adjusted relation against collapse, oppositely bowed resilient strips each mounted upon the outer end of one of said sections, each strip at each extremity being bent to provide lateral walls at right angles to the face of the strip, resilient ears extending over said walls, a lever supporting member having portions projecting over the ears, and levers mounted in said lever supporting member and engageable with said ears to hold them closed. 115 120 125

6. In a stretcher of the character described, longitudinally expandible stretcher 130

members, and laterally adjustable stretcher members carried by the longitudinally expansible members and each including divergent arms, each of said arms of each 5 stretcher member being freely movable with relation to the stretcher section to which it is attached, said arms being normally held in divergent relation and at more than a

right angle to the corresponding stretcher section.

In testimony whereof I hereunto affix my signature in the presence of two witnesses.

ABRAHAM FISCHER.
